UNITED STATES PATENT OFFICE

EDWARD B. STEPHENSON, OF WASHINGTON, DISTRICT OF COLUMBIA

SUBAQUEOUS SYSTEM OF ARTILLERY FIRE ADJUSTMENT

Application filed January 9, 1925. Serial No. 1,510.

(GRANTED UNDER THE ACT OF MARCH 3, 1883, AS AMENDED APRIL 30, 1928; 370 O. G. 757)

This invention described herein may be manufactured and used by or for the Government for governmental purposes, without the payment to me of any royalty thereon.

5 This invention relates to a subaqueous system of artillery fire adjustment, utilizing water as a transmitting medium, the impact of the projectile striking the water as a source of the pressure wave or pulse and hydrophones as detectors.

10 One of the principal objects of this invention is to effect a new and improved system of subaqueous artillery ranging automatically functioning to furnish data necessary 15 to afford a rapid determination of the range and an accurate adjustment of the artillery fire.

Another important object of this invention is to provide a system which, owing to its 20 electro-mechanical character, will enable a rapid and accurate determination of the range, irrespective of prevailing atmospheric conditions, darkness, and errors of observation, factors which heretofore tended to seri- 25 ous inaccuracy and materially hampered operations.

This invention is based on the theory that— 30 (1) a projectile striking the water produces a pressure pulse or wave having a circular wave front and capable of traveling with uniform velocity and without distortion over long distances, (2) there is a time interval between the arrival of the pressure wave or pulse at two or more stations located at defi- 35 nitely known and unequally distant points, (3) the differences in the time of arrival at the different stations, taken in connection with the constant, known rate of propagation of the pressure wave in water will enable 40 determination of the source of the disturbance, (4) the source of the pressure wave, likewise the position of the target, being known the correct artillery adjustment can readily be ascertained.

45 In the accompanying drawings in which corresponding parts are indicated by similar reference characters:

Fig. 1 is a diagrammatic view illustrating a fragment of a coast line, a coast defense 50 battery consisting of a series of forts, a cen-

trol zone of fire, the practical lateral limits of such fire and a plurality of suitably located hydrophone detector stations.

Fig. 2 is a diagrammatic view illustrating a fragment of coast line, a series of suitably 55 submerged detectors, a central station, the receiving sets at the central station and their electrical connections with the detectors.

Fig. 3 is a transverse vertical section of a type of hydrophone used in connection with 60 this invention.

Fig. 4 is a trigonometrical diagram for use in explaining the method used in determining the unknown source of the pressure wave.

Fig. 5 is a diagrammatic view illustrating 65 one of the submerged microphones, its indicia and anchoring arrangement.

Fig. 6 is a diagrammatic view illustrating the application of the stringed galvanometer to the optical system and photographic re- 70 cording means used therewith.

In the present system of artillery ranging, observations concerning the result of the artillery fire are made from elevated positions on land or from aerial outposts, in the nature 75 of airplanes or balloons, the observer transmitting his observations by manual signaling, wireless, or telephone, dependent on the exigencies of the situation, to the battery commander who then makes the necessary correc- 80 tions for adjustments of fire.

Manifestly the accuracy and efficiency of this system are largely governed by the ability of the observer, atmospheric conditions, darkness, etc. and while answering the purpose in the absence of a superior system, are far from satisfactory. It is therefore the aim and purpose of this invention to provide a system which is largely automatic in its 85 operation, and not dependent on or in any 90 way influenced by the factors specified.

Briefly stated, this invention consists in producing a characteristic pressure wave or pulse, through the instrumentality of a projectile striking the water, determining the 95 origin of the pulse, plotting the course of a moving target, and then correlating the pulse origin with the location of the target to obtain the range adjustment.

By locating the detectors in this manner, 100

the arrival of the pressure wave at the respective stations is immediately indicated at the central station by the galvanometer, with which is associated suitable timing and recording mechanism, and by noting the differences in time of arrival of the pressure wave at three or more of these stations and employing this data in conjunction with the known rate of pressure wave propagation, 10 the source of the disturbance, as well as the relation of such disturbances to the target, can be quickly determined, assuming the position of the target is known.

In order to facilitate the discussion of this 15 invention, it will be further considered under the following headings:—"Detector installation", "Central station", "Mathematical determination of the source of the pressure wave", "Plotting or tracking the course 20 of the target", and "Conclusion".

In the illustrated embodiment of this invention there is shown, for descriptive purposes, a portion of a coast line A, a coast fortification B, consisting of three artillery 25 batteries C, the latter having a central zone of fire indicated by the area D, and a practical lateral limit of fire shown by the radial lines E.

Detector installation

30 When a projectile strikes the water a pressure pulse is generated, characterized by its brief duration and extensive amplitude. To locate the source of this pressure wave or 35 pulse a plurality of hydrophone detector stations, six in number, and indicated M_1 , M_2 , M_3 , M_4 , M_5 , and M_6 , are submerged off shore at a distance sufficient to avoid water noises on shore and afford an uninterrupted 40 water path between the stations and the source of the pressure wave.

These stations are positioned in the arc of a circle and at equal distances apart, the chord of the arc corresponding to the radius 45 F, of a circle having its center located at the point of maximum accuracy G, in the central zone of fire D.

The hydrophone detector stations used with this invention are of special design and 50 embody a microphone button 1, mounted interior of a mine casing 2, suitably anchored as at 3; the position of the mine casing being shown by a suitable float 4, which if desirable may be provided with a signal flag 55 or the like.

The microphone button 1, consists essentially of two polished graphite plates 5 and 6, placed parallel to one another and separated about $\frac{1}{16}$ ", the intervening space being partially filled with fine carbon granules. One of the plates is attached to a diaphragm allowing it to vibrate back and forth along a line perpendicular to its surface to alternately compress and release the carbon 65 granules. This movable plate is rigidly at-

tached as at 6¹, to a suitable mounting with the casing as shown in Figure 3.

The motion of the diaphragm produced by the action of the pressure wave causes corresponding changes in the pressure between the carbon granules, varies the resistance in the primary circuit of the transformer and actuates the galvanometer and other apparatus at the central station to produce a record of the wave.

Central station

The several detectors are connected to a receiving set, located at the fortification and referred to as a central station. Each set includes a battery circuit 7, also a primary coil 8, of a transformer 9, the secondary coil 10, of the latter including a galvanometer 11.

Galvanometer 11, is of special design operating on the principle that a wire carrying a current through a magnetic field will be deflected in a plane perpendicular to the direction of the wire and that of the magnetic field. The wire may be of platinum or tungsten and is approximately .0004" in diameter. Under the proper tension such a wire will follow closely the variations in the impressed electro motive force for all ordinary frequencies. This is an important feature necessary to insure that the record obtained will be as characteristic of the original pressure wave as the apparatus will permit.

To secure a permanent record of the vibrations of the galvanometer strings, as well as the time of such vibration, shadows of the strings are cast upon a movable photographic film by a suitable optical arrangement, designated 12 in Fig. 6: hence any movement of the strings will be reproduced on the film.

To obtain the exact time the indications are received, a further mechanism in the nature of a revolving disk 13, synchronized with a tuning fork casts thin transverse shadows across the film record at 1/100 second intervals, with thicker shadows every $\frac{1}{10}$ second.

The galvanometer, recording and timing apparatus just described are fully discussed in Engineer Bulletin No. 63, entitled "Sound ranging", prepared by E. B. Stephenson.

Mathematical determination of the source of the pressure wave

Assuming that the disturbance produced by the impact of a projectile striking the open water is a pressure pulse or wave characterized as stated, and that the time intervals elapsing between the arrival of the impulse at three or more stations suitably spaced are known, the origin of the disturbance can readily be located.

Consider two stations such as M_1 and M_2

of Fig. 1, and suppose that the wave arrives at M_1 at the time T_1 and at M_2 at the time T_2 . There are an infinite number of possible positions of the source which will give the time interval $T_2 - T_1$ between the arrival of the wave at M_1 and M_2 , however all these positions must be on a hyperbola of which M_1 and M_2 are the foci, since such an hyperbola is the locus of a point which moves so that the difference of its distances from the foci is constant.

Referring to Fig. 4, if M_1 and M_2 are two hydrophone stations, L_{12} the distance between M_1 and M_2 , and $R-O-W$ a circle circumscribed about M_2 as a center with radius $r = V(T_2 - T_1)$ where V is the velocity of the pressure wave in water, the hyperbola XC' will be the locus of the centers of the circles which touch the circle $R-O-W$ and pass through M_1 .

If the origin of the pressure wave is at a distance which is large compared with the distance M_1M_2 , the arc OM_1 of the wave front approximates a straight line and in the limit will be a straight line passing through M_1 and touching the circle whose center is M_2 while the origin of the pressure wave will lie in the perpendicular bisector of the tangent OM_1 .

The perpendicular bisector of the tangent will pass through the middle point of the line M_1M_2 and will touch the hyperbola considered above at infinity. It is therefore the asymptote of the hyperbola.

For practical purposes, in the graphical location of the origin of the pressure wave on a plotting board, it is highly desirable to plot asymptotes, which are straight lines, rather than hyperbolæ. We may therefore establish a relation between L_{12} , the distance between the hydrophone stations M_1 and M_2 , the time difference t_{12} , between the times T_1 and T_2 of the arrival of the wave at M_1 and M_2 respectively, and θ_{12} the angle between the perpendicular bisector of the line M_1M_2 and the asymptote XC of the hyperbola XC' .

In the figure

50 $\phi_{12} = \angle OM_1M_2$

$$\therefore \sin \theta_{12} = \frac{OM_2}{M_1M_2} = \frac{V(T_2 - T_1)}{L_{12}} = \frac{Vt_{12}}{L_{12}} = \frac{t_{12}}{m_{12}}$$

55 where m_{12} is the time length of base, or the time taken by the pressure wave to travel a length equal to that of the base.

Hence for each pair of hydrophones a scale may be graduated around the edge of a plotting board in such a way that if the center of the base is laid on the division of said scale corresponding to the observed time interval t the string is the asymptote of the hyperbola in which the origin of the pressure wave lies. The intersection of two or more such

strings would locate the point on the plotting board.

Plotting or tracking the course of the target

For the purpose of this invention, any of the prevailing visual methods of plotting the course of a vessel may be employed, but in order to render the system entirely automatic and obtain the required data as quickly as possible, it has been found advantageous to employ at least two water stations connected by multiple conductor cable to two shore stations. Each water station embodies two or more hydrophones mounted on a heavy tripod, which rests on the sea bottom, the hydrophones being suitably separated to form a base line. The location of the mid-point of the base line and its orientation are accurately known and the stations are disposed so that the perpendicular bisectors of the base lines will intersect at a wide angle in the zone of fire. Each of the shore stations include a suitable supply of electrical power, the necessary switching apparatus and an acoustic or electrical compensator.

In the use of this apparatus the operator listens to the continuous noise produced by the propeller of the ship and transmitted through the water. If the location of the ship coincides with the line of the perpendicular bisector of the base line, the sound appears to be directly in front of the listener. On the other hand, should the sound appear to emanate from a point other than directly in front of the operator, the latter rotates the compensator until the sound appears directly in front and reads the index of the compensator when a time interval bell is sounded. By previous calibration a scale can be made for the compensator, giving the angular deviation of the sound source from the perpendicular base line of the water station. Intersections from two or more water stations give the location of the ship, on the plotting board and consecutive readings its course or track.

The preceding arrangement forms no part of the present invention and is recited merely to illustrate the various steps incidental to the method under consideration.

In the practical application of one type of this invention two plotting boards are employed, corresponding to the area previously indicated as the zone of fire, each of the boards being suitably sub-divided according to the requirements of the problem. On one board, by means of the agencies described, the course of the target is plotted; on another is indicated the location of the origin of the pressure wave, hence determination of the requisite artillery adjustment thus becomes a simple mechanical proposition. Correlating the location of the source of the pressure wave as shown on one plotting board with respect to the position of the target on the other.

Conclusion

In conclusion, it may be said, the proposed system provides an ideal solution of the problem of artillery fire adjustment, and possesses advantages in the nature of speed and accuracy not found in any of the existant systems, and this is especially true with respect to ranging in air, because:

- 10 1. Water is a more homogeneous medium than air.
2. The temperature variation is less.
3. The velocity of tides or currents is usually less than the normal wind velocity.
- 25 and they are more constant in direction and velocity during a given interval so that corrections may be more accurately determined.
4. In general the tidal or current flow can be accurately determined and will be perpendicular to the hydrophone base where its effect in causing error will be a minimum.

5. The elimination of interference is simpler because the hydrophone is practically unaffected by sounds in the air.

25 Tests made with this system have shown that if a shell enters the water ten miles from the farthest microphone on the base, 11 seconds will be required for the pressure wave to reach such microphone, 6 seconds for the development of the film, 18 seconds to read the latter, and 10 seconds to report results, which thus gives a permanent record in 45 seconds.

In view of the foregoing, it is evident this 35 invention provides a simple, efficient and expeditious method for accurately determining the range of a target, as well as a system by which the time of flight and range of a projectile may be rapidly ascertained, since the 40 principles underlying both problems are substantially identical.

Having defined my invention, what I claim as new and wish to secure by Letters Patent is:

45 1. A method of subaqueous artillery fire adjustment comprising utilization of the pulse generated by a projectile striking a fluid medium, to determine the point of projectile impact.

50 2. A method of subaqueous artillery fire adjustment comprising production of a pulse in a liquid medium and utilization of such pulse to determine its point of origin.

3. A method of subaqueous fire adjustment 55 comprising production in a fluid medium of a pulse characterized by its duration and amplitude and utilization of such pulse to determine its origin.

4. A method of subaqueous artillery fire 60 adjustment comprising determination of the point at which an object enters a fluid medium by utilization of the resulting characteristic pulse.

5. A method of subaqueous artillery fire 65 adjustment comprising the determination of

the point at which a projectile enters a fluid medium by utilization of the resulting pressure pulse.

6. A method of subaqueous artillery fire adjustment consisting in determining the 70 point at which a projectile enters a fluid medium by utilizing the resulting pressure pulse, plotting the course of a target and corelating the point at which the projectile enters such medium with reference to the 75 location of the target, to adjust the range.

7. A method of subaqueous artillery fire adjustment consisting in producing a characteristic pressure pulse through the instrumentality of an object striking a fluid medium utilizing this pulse to ascertain its 80 origin and corelating the point of pulse origin with reference to a target of known location.

8. A method of subaqueous artillery fire 85 adjustment consisting in producing a characteristic pressure pulse by means of an object striking a fluid medium, utilizing this pulse to obtain the point at which the object contacted with the fluid medium, and corelating such point with reference to a target 90 of known location.

9. A method of subaqueous artillery fire adjustment consisting in producing a characteristic pressure pulse by means of a projectile striking a fluid medium, utilizing the 95 resulting pulse to ascertain the point of impact, plotting the course of a moving target and corelating the point of impact with reference to the location of the target to effect 100 an adjustment of artillery fire.

10. A method of subaqueous artillery fire adjustment consisting in producing in a liquid medium a pulse characterized by its duration and amplitude, utilizing such pulse 105 to determine its origin, plotting the course of a moving target and corelating the point of pulse origin with reference to the location of target to effect an adjustment of 110 artillery fire.

11. A method of subaqueous artillery fire adjustment consisting in producing a characteristic pressure pulse, determining its origin, plotting the course of a moving target, and then corelating the point of pulse 115 origin with the location of the target to effect an adjustment of artillery fire.

12. A method of subaqueous artillery fire adjustment consisting in producing a characteristic pressure pulse, determining its origin, ascertaining the exact location of a moving target and then corelating the point of pulse origin with reference to the location 120 of the target to effect an adjustment of artillery fire.

13. A method of subaqueous artillery fire adjustment consisting in producing a pressure pulse characterized by its duration and amplitude, ascertaining the exact location of a moving target and then corelating the point 125

of pulse origin with reference to the location of the target to effect an adjustment of artillery fire.

14. A method of subaqueous artillery fire adjustment consisting in producing a characteristic pressure pulse by means of a projectile striking a fluid medium, determining the origin of such pulse, plotting the course of a moving target and then corelating the point of pulse origin with reference to the location of the target to effect an adjustment of artillery fire.

15. A method of subaqueous artillery fire adjustment consisting in generating a characteristic pulse through the instrumentality of a projectile striking a fluid medium and determining the point of pulse origin with reference to a target of known location.

16. A method of subaqueous artillery fire adjustment consisting in utilizing a characteristic pulse through the instrumentality of a projectile striking a fluid medium, plotting the course of a moving target, and determining the point of pulse origin with reference to the location of the target to effect an adjustment of artillery fire.

17. A method of subaqueous artillery fire adjustment consisting in producing a pressure pulse characterized by its brief duration and amplitude, indicating the arrival of such pulse at a series of stations, measuring the difference in time of arrival at several of the stations and employing this data in connection with the known rate of pulse travel in a liquid medium to determine the point of pulse origin with reference to a target of known location.

18. A method of subaqueous artillery fire adjustment consisting in producing a characteristic pressure pulse through the instrumentality of a projectile striking a fluid medium, indicating the arrival of such pulse at a series of stations, measuring the difference in time of arrival at several of the stations, and employing this data in connection with the known rate of pulse travel in a liquid medium to determine the point of pulse origin with reference to a target of known location.

50 19. A method of subaqueous artillery fire adjustment consisting in producing a characteristic pressure pulse through the instrumentality of projectile impact with a fluid medium, indicating the arrival of such pulse at a series of stations, measuring the difference in time of arrival at several of the stations, employing this data in connection with the known rate of pulse travel in a liquid medium to determine the point of pulse origin, plotting the course of a moving target, and then corelating the origin of the pressure pulse with reference to the location of the target to effect an adjustment of artillery fire.

65 20. A method of subaqueous artillery fire

adjustment consisting in producing a characteristic pressure pulse by means of projectile impact with a fluid medium, indicating the arrival of such pulse at a series of submerged detector stations, measuring the difference in time of arrival of the pressure pulse at three or more of these stations, and employing this data in connection with the known rate of pressure pulse travel in a liquid medium to determine the point of pulse origin with reference to a target of known location.

70 21. A method of subaqueous artillery fire adjustment consisting in producing a characteristic pressure pulse by means of projectile impact with a fluid medium, indicating the arrival of such pulse at a series of submerged detector stations, measuring the difference in time of arrival of the pressure pulse at three or more of these stations, and employing this data in connection with the known rate of pressure pulse travel in a liquid medium to determine the point of pulse origin, plotting the course of a target, and corelating the point of pulse origin, with reference to the location of the target to effect an adjustment of artillery fire.

80 22. A method of subaqueous artillery fire adjustment consisting in producing a pressure pulse characterized by its brief duration and extensive amplitude, indicating the arrival of such pulse at a series of submerged detector stations, the latter being arcuately arranged and located at equal distances apart, measuring the difference in time of arrival at several of the stations, and employing this data in connection with the known rate of pulse travel in a liquid medium to determine the point of pulse origin with reference to a target of known location.

90 23. A method of subaqueous artillery fire adjustment consisting in producing a pressure pulse characterized by its brief duration and extensive amplitude, indicating the arrival of such pulse at a series of submerged detector stations, the latter being arcuately arranged and located at equal distances apart, measuring the difference in time of arrival at several of the stations, employing this data in connection with the known rate of pulse travel to determine its point of origin, plotting the course of a moving target and then corelating the origin of the pressure pulse with reference to the location of the target to effect an adjustment of the pulse.

100 24. A method of subaqueous artillery fire adjustment consisting in producing a pressure pulse characterized by its brief duration and extensive amplitude, indicating the arrival of such pulse at a series of submerged detector stations, the latter being located at equal distances apart and arranged in the arc of a circle whose center coincides with the point of maximum accuracy in the zone of

115

120

125

130

fire, measuring the difference in time of arrival at three or more of these stations, and employing this data in connection with the known rate of pulse travel in a liquid medium 5 to determine the point of pulse origin with reference to a target of known location.

25. A method of subaqueous artillery fire adjustment consisting in producing a pressure pulse by means of projectile impact with 10 a liquid medium, such impulse being characterized by its brief duration and extensive amplitude, indicating the arrival of this pulse at a series of submerged detector stations, the latter being located at equal distances apart 15 and arranged in the arc of a circle whose center coincides with the point of maximum accuracy in the zone of fire, measuring the difference in time of arrival at three or more of these stations, and employing this data 20 in connection with the known rate of pulse travel in a liquid medium to determine the point of pulse origin with reference to a target of known location.

26. A method of subaqueous artillery fire adjustment consisting in producing a pressure pulse by means of projectile impact with 25 a liquid medium, such pulse being characterized by its brief duration and extensive amplitude, indicating the arrival of this pulse at a series of submerged detector stations, the latter being located at equal distances apart and arranged in the arc of a circle whose center coincides with the point of maximum accuracy in the zone of fire, measuring 30 the difference in time of arrival at three or more of these stations, employing this data in connection with the known rate of pressure pulse travel in a liquid medium to determine the point of pulse origin, plotting 35 the course of a moving target and correlating the point of pulse origin with reference to the location of the target to effect an adjustment of artillery fire.

27. A method of subaqueous artillery fire adjustment consisting in producing a pressure pulse, characterized by its brief duration and extensive amplitude, electro-mechanically indicating the arrival of such pulse at a series of submerged detector stations, measuring the difference in time of arrival at three or more of these stations, employing this data in connection with the known rate of pulse travel in the liquid medium to determine the point of pulse origin, 50 plotting the course of a moving target and correlating the point of pulse origin with reference to the location of the target to effect an adjustment of artillery fire.

28. A method of the character described 60 consisting in producing a characteristic pressure pulse at a predetermined point in a fluid media and utilizing the effect of such pulse on devices responsive thereto for the purpose of determining the location of said point.

29. A subaqueous method of artillery fire

adjustment comprising production of a characteristic pulse in a fluid medium and utilization of said pulse to determine the origin, said pulse being of brief duration, having a circular wave front of considerable amplitude and being capable of travelling long distances without distortion or absorption. 70

30. A subaqueous method of artillery fire adjustment comprising utilization of a characteristic pulse produced by an object striking a fluid medium to determine the point of its impact, said pulse being of brief duration, having a circular wave front of considerable amplitude and being capable of travelling long distances without distortion or absorption. 75

31. A subaqueous method of artillery fire adjustment comprising generation of a pulse by means of a projectile striking a fluid medium, determination of the point of projectile impact through the instrumentality of said pulse, said pulse being of brief duration, having a circular wave front of considerable amplitude and being capable of travelling long distances without distortion or absorption. 80

32. A subaqueous method of fire adjustment comprising a determination of the point at which an object enters a fluid medium by utilization of the resulting characteristic pulse, said pulse being of brief duration and having a circular wave front of considerable amplitude and being capable of travelling long distances without distortion or absorption. 85

33. A method of the character described consisting in producing a characteristic pressure pulse at a predetermined point in a fluid medium and utilizing the effect of such pulse for the purpose of determining the location of said point, said pulse being of brief duration having circular wave front of considerable amplitude and being capable of travelling long distances without distortion or absorption. 90

34. A method of the character described consisting in producing a characteristic pressure pulse at a predetermined point in a given medium and utilizing the effect of such pulse on devices responsive thereto, for the purpose of determining the location of said point, said pulse being of brief duration, having a circular wave front of considerable amplitude and being capable of travelling long distances without distortion or absorption. 100
